UNITED STATES PATENT OFFICE.

CLARENCE A. STRONG, OF O'NEILL, NEBRASKA, ASSIGNOR OF ONE-HALF TO CHARLES M. DALY, OF O'NEILL, NEBRASKA.

PELT STRETCHER.

Application filed April 30, 1925. Serial No. 26,978.

My invention aims to provide an exceptionally simple and inexpensive, yet a very desirable, efficient and easily operated device for stretching pelts from all fur-bearing animals, it being of course understood that the stretchers must be made in different sizes.

With the foregoing in view, the invention resides in the novel subject matter hereinabove described and claimed, the description being supplemented by the accompanying drawing.

Figure 1 is a side elevation.

Figures 2, 3 and 4 are detail sectional views on lines 2—2, 3—3 and 4—4 of Fig. 1.

In the drawing above briefly described, the numerals 1 and 2 designate two wooden slats, each of which is transversely tapered as shown in Fig. 4. These slats are also preferably tapered longitudinally to provide each one with a rather pointed, tapered end 3, and with a butt end 4. Secured to opposite sides of the butt end 4 of slat 1, are two wooden strips 5, nails 6 being preferably provided for securing said strips and the slat 1 together. The strips 5 project laterally in one direction from the slat 1, extend across the opposite sides of the slat 2, and have their outer ends secured by nails 7 or the like against opposite sides of a spacing block 8. This block and the portions of the strips 5, projecting laterally from the slat 1, form a lateral guide in which the butt end of the slat 2 is freely movable, so that after a pelt has been tacked to the slats 1 and 2, one end of said pelt may be stretched by manually forcing the butt end 4 of the slat 2 away from the slat 1, within the above named guide. Then, by any preferred means, but preferably by a nail 9 driven through the strips 5 and the slat 2, the latter may be secured against return to its initial position. Then, to spread the tapered ends 3 of the slats 1 and 2 and stretch the other end of the pelt, I provide a wedge slat 10 which is insertable between the strips 5 and between the slats 1 and 2. This wedge slat is adapted to contact with the inner edges of the slats 1 and 2, only at the tapered ends of the latter as shown in Fig. 1 and it will thus be seen that when it is forced in a proper direction, said ta-

pered ends of the slats 1 and 2 will be laterally spread. The front end of the slat 10 is preferably somewhat pointed as indicated at 11, for engagement with the nose cartilage of the pelt, to assist in longitudinally stretching the latter. After this wedge slat 10 has been forced into the desired position, it is locked by any desired means, but preferably by a nail 12 driven into it and through the strips 5.

The device is exceptionally simple and inexpensive, may be readily constructed from materials easily obtained by any trapper, will be very efficient and durable, and may be easily connected with or disconnected from a pelt, without any danger of injuring the latter in any manner.

Excellent results have been obtained from the exact details disclosed and they are therefore preferably followed. However, within the scope of the invention as claimed, slight modifications may of course be made.

I claim:

A pelt stretcher comprising two relatively movable wooden slats disposed in a common plane and spaced apart laterally, each slat having a butt end and a tapered end, a pair of straight strips transverse to said slats at the butt ends of the latter, said strips being secured to opposite sides of one of said slats and extending across the sides of and beyond the other slat, a spacer to which the outer ends of said strips are secured to form therewith a guide in which said other slat is freely movable toward and from said one slat, means for securing the movable slat with respect to said guide after it has been laterally forced from the relatively stationary slat to stretch one end portion of a pelt, and a wedge slat adapted to be inserted through said guide between the relatively stationary and movable slats after the latter has been secured, said wedge slat being adapted to spread the tapered ends only of said relatively stationary and movable slats and being of a length to project beyond said tapered ends for engagement with the nose of the pelt.

In testimony whereof I have hereunto affixed my signature.

CLARENCE A. STRONG.
